CLAIM

The ornamental design for a brassiere, as shown and described.

DESCRIPTION

FIG. 1 is a front perspective view of a brassiere showing the claimed design;

FIG. 2 is a rear perspective view thereof;

FIG. 3 is a front view thereof;

FIG. 4 is a rear view thereof;

FIG. 5 is a left side view thereof; and,

FIG. 6 is a right side view thereof.

The broken lines in the figures show portions of the brassiere that form no part of the claimed design.

1 Claim, 6 Drawing Sheets
